UNITED STATES PATENT OFFICE.

NIKOLAI L. BERNATZKY, OF ST. PETERSBURG, RUSSIA.

SWIMMING-APPARATUS GOWN.

1,109,504.

Specification of Letters Patent.

Patented Sept. 1, 1914.

Application filed February 24, 1913. Serial No. 750,407.

To all whom it may concern:

Be it known that I, NIKOLAI L. BERNATZKY, subject of the Emperor of Russia, residing at Malaya Posadskaya No. 6, St. Petersburg, Russia, have invented new and useful Improvements in Swimming-Apparatus Gowns, of which the following is a specification.

This invention relates to improvements in means for supporting a person in water.

The object of the invention is to provide means to permit a person to float in case of ship wreck or other causes, or for making scientific investigations in water.

The invention also comprehends improvements in the details of construction and arrangement of parts which will be hereinafter described and particularly pointed out in the claims.

In the drawings Figure 1 is a perspective view of my improvement. Fig. 2 is a vertical section of the same. Fig. 3 is a top plan view. Fig. 4 is a side elevation illustrating a slight modification.

1 indicates the body portion of a tight garment to fit the body and limbs of the wearer, and 2 the head portion. In lieu of the hood 2, a helmet may be employed. The garment is made from suitable elastic material, impervious to water, and is lined on the inside with wool or like material to protect the wearer from cold.

4 indicates a keel which fits between the legs 5 of the body portion of the garment, and extends well on the front and rear, as clearly shown in the drawing. On the upper edge of the front and rear portions of the keel, are receptacles 6 and 7, filled with air or gas, to provide floats to sustain a person wearing the apparatus, in the water. These floats are held in position by straps 9, which extend from one float to the other, and over the shoulders of the wearer. The floats support cases 10—10, which may contain food, or instruments to be used while the instrument is in use. The keel may be employed as a rudder to steer the user in the water, and to facilitate the steering, I provide a lever 13, secured to the rear portion of the keel, and extending forwardly in convenient reach of the hands of the user. A frame 14, extends upwardly on each side of the garment to a point some distance above the head portion. To the lower ends of the frame are secured weights 15, and at the upper end is a sail 16. In lieu of the

sail I may provide a propeller 17, located at the rear of the apparatus, and operated by any suitable means such as an electric air or gas motor conveniently located in the 60 casing 18.

In operation, the user applies the body portion of the garment to his body, and because of the material being elastic the walls of the openings 20, at the top will snugly 65 fit the neck and prevent ingress of water. Then the head portion is applied, the lower edge of same engaging over the upper edge of the body portion and also fits the neck tight, and further prevents the admission 70 of water. The garment having been adjusted on the wearer, the straps and keel are adjusted and the apparatus is now in condition for use. When in the water the floats will sustain the weight of the body, and the 75 wind contacting with the sail will cause the person to move about, the direction of travel being controlled by manipulating the lever and keel. The weights steady the apparatus and tend to prevent forward or back- 80 ward tilting.

The invention is extremely simple in construction, and is effective in operation. In case of ship wreck, a person may survive in the water for a number of days without discomfort.

In the garment above the crotch, are bags 40, to receive liquid and solid refuse from the body. These bags may be opened from the inside, and pipes 41, lead to the exterior 90 for draining purposes. The pipes may be controlled by suitable valves 42.

What I claim is:—

1. An apparatus of the class described, comprising a garment, a keel, floats supported by the keel, means for supporting the floats to the user of the garment, means for propelling the apparatus, and means for deflecting the keel to steer the apparatus.

2. An apparatus of the class described, comprising an elastic garment having leg portions, a keel fitting between the leg portions, floats supported on the keel, float supporting means extending over the shoulder portions of the garment, means by which 105 the apparatus may be propelled, and means for deflecting the keel to steer the apparatus.

3. An apparatus of the class described comprising an elastic garment having leg 110 portions, a keel fitting between the leg portions, floats supported on the keel, float sup-

- porting means extending over the garment, means by which the apparatus may be propelled, and means for shifting the position of the keel to steer the apparatus.
5. An apparatus of the class described, comprising an elastic garment composed of body and head sections to engage the person using the apparatus, said garment having a lining, a keel, floats mounted on the keel, 10 means for supporting the floats on the garment, a frame on the garment, and a sail carried by the frame.
5. An apparatus of the class described, comprising an elastic garment including leg 15 portions, a keel, floats, a frame supported on the elastic garment, said frame extending down each leg portion of the garment and above the latter, a sail on the upper portion of the frame, and weights at the lower ends

of the frame adjacent the leg portions to 20 balance the apparatus.

6. An apparatus of the class described comprising a garment including leg portions, a keel extending between the leg portions, floats on the opposite ends of the keel, straps 25 extending from the floats and over the shoulder portions of the garment, a casing mounted on each float, an open frame extending down the leg portions of the garment and above the latter, and a sail at the upper end 30 of the frame.

In testimony whereof I have signed my name to this specification in the presence of two subscribing witnesses.

N. L. BERNATZKY.
